UNITED STATES PATENT OFFICE.

BENJAMIN SILVERMAN, OF CHATTANOOGA, TENNESSEE, ASSIGNOR OF ONE-HALF TO
J. RUSSEL EARP, OF CHATTANOOGA, TENNESSEE.

COMB.

Application filed November 7, 1923. Serial No. 673,256.

To all whom it may concern:

Be it known that I, BENJAMIN SILVERMAN, a citizen of the United States, residing at Chattanooga, in the county of Hamilton 5 and State of Tennessee, have invented certain new and useful Improvements in Combs, of which the following is a specification.

This invention relates to hair dressing 10 and has special reference to a device for straightening wavy or kinky hair.

More particularly the invention relates to an improved hair straightening comb.

One important object of the invention is 15 to improve the general construction of devices of this character.

A second important object of the invention is to provide a comb of this character having separate metallic teeth secured in 20 position in an improved and novel manner.

A third important object of the invention is to provide an improved comb for the purpose set forth wherein the teeth are curved in a peculiar manner and wherein the 25 handle and tooth portions are separable so that the latter may be reversed in its relation to the handle thus changing the curvature from right to left or from left to right.

A fourth important object of the invention 30 is to provide a novel means for securing the tooth portion of such a comb to its handle.

With the above and other objects in view as will be hereinafter apparent, the invention 35 consists in general of certain novel details of construction and combinations of parts hereinafter fully described, illustrated in the accompanying drawings and specifically claimed.

40 In the accompanying drawings like characters of reference indicate like parts in the several views, and:

Figure 1 is a side elevation of the complete comb in the form using straight teeth.

45 Figure 2 is a longitudinal vertical section of the tooth portion of the device showing the method of assembly.

Figure 3 is a perspective view showing part of the tooth portion partly assembled.

50 Figure 4 is an enlarged end view of Figure 1.

Figure 5 is a modified end view showing the teeth curved.

55 Figure 6 is a section on the line 6-6 of Figure 2.

Figure 7 is a perspective view of one of the curved teeth used herewith.

In the embodiment of the invention here disclosed there is shown a handle 10 having an opening extending longitudinally therethrough and provided on one end with a ferrule 11.

The comb proper consists of a series of metallic teeth 12 and a pair of metallic end teeth 13 which are thicker than the teeth 12. 65 These teeth are each tapered laterally from butt 14 to point 15 and are provided with curved sides 16, the sides being either equally convex as shown in Figure 4 or one side being convex and the other concave as 70 shown in Figure 5. Between these teeth at the butt portions are located metallic spacers 22 and each tooth and spacer is provided at the butt with a circular opening 17 and somewhat closer to the point but still near 75 the butt with a square opening 18. These openings are arranged to register when the device is assembled and, in order to hold the teeth together a square rod 20 is run through the square openings, being riveted at the end 80 as shown at 21. This rod has its other end received in the opening 18 of a supplemental spacer 22 forming a washer against which the ferrule 11 bears. The rod 20 is 85 held in place by the head 23 of a bar 24, this head engaging over the head 21 as best seen in Figure 2. The bar 24 passes through the openings 17 and through the handle 10, being provided with a threaded end projecting from the handle for the reception 90 of a butterfly nut 25. Thus the rod 24 serves to hold all the parts in assembled relation, while the rod 20 prevents the teeth from misalignment.

In use the device is simply heated and 95 drawn through the hair, the heated teeth acting to iron out the waves or kinks in the hair, thus leaving it smooth and straight.

It will be obvious that, with teeth such as shown in Figure 7 the assembly may be 100 made to cause the teeth to curve to one side or the other as desired.

There has thus been provided a simple and efficient device of the kind described and for the purpose specified.

105 Having thus described the invention, what is claimed as new, is:

In a comb of the class described, a tooth portion comprising a series of teeth, a series of spacers arranged alternately with said 110

teeth said teeth and spacers having registering non-circular openings therein, a bar passing through said openings and conforming in cross section to the openings to fit closely therein and prevent relative rotation of the teeth and spacers, said bar having a head on one end, a second bar passing through the teeth and spacers and having a head on one end overlapping the head on 10 the first bar to retain it in position, a

handle removably mounted on the remaining end of the second bar and having a ferrule engaging one end of the tooth portion, said second bar projecting through the handle and having its projecting end threaded, and a thumb nut mounted on said threaded end to draw the parts together. 15

In testimony whereof I affix my signature

BENJAMIN SILVERMAN
